UNITED STATES PATENT OFFICE.

CHARLES L'ENFANT, OF NEW YORK, N. Y.

CONTAINER.

Application filed February 5, 1926, Serial No. 86,131. Renewed August 1, 1928.

This invention relates to containers, and more particularly to a case or container for cigarettes, cigars, and other commodities which, when closed presents a neat and attractive appearance and which is so constructed as to permit of easy and quick access to the contents thereof.

It is another object of the invention to provide a case or container of this character having an article holder open at one of its ends and an enclosing case therefor embodying integrally connected resiliently yieldable side walls having rounded ends movable towards and from each other and adapted to close the open end of the article holder. Thus, when the holder is bodily moved in one direction between the side walls of the case to exert pressure against the rounded ends thereof, said ends of the case walls are sprung apart and the open end of the holder projected beyond the same to enable the contents thereof to be easily withdrawn.

It is a further object of the invention in one embodiment thereof to provide the side walls of the case with integral means confining the article holder between said case walls against lateral shifting movement relative thereto and to also provide suitable means whereby the article holder may be supported in its projected position.

It is a further general object of the invention to provide a case or container having the above novel features which is of exceedingly simple construction and can therefore, be manufactured and sold at comparatively small cost.

With the above and other objects in view, the invention consists in the improved container and in the form, construction and relative arrangement of its several parts as will be hereinafter more fully described, illustrated in the accompanying drawings and subsequently incorporated in the subjoined claims.

In the drawings, wherein I have illustrated several simple and practical embodiments of my invention, and in which similar reference characters designate corresponding parts throughout the several views,—

Figure 1 is a perspective view of one form of my improved case or container showing the same closed;

Fig. 2 is a similar view showing the container open;

Fig. 3 is a longitudinal sectional view with the parts in closed position;

Fig. 4 is a similar view showing the container open as in Fig. 2;

Fig. 5 is a perspective view similar to Fig. 1, showing a slightly modified form of the device;

Fig. 6 is a sectional view of said modification similar to Fig. 4;

Fig. 7 is a perspective view similar to Fig. 5 showing another embodiment of the invention, and

Fig. 8 is a longitudinal sectional view illustrating a further alternative construction.

Referring in detail to the drawings, and for the present more particularly to Figs. 1 to 4 thereof, the container as therein shown includes an article holder 5 of general parallelogrammatic form and which may be provided with a central transversely disposed partition 6 to divide the holder into separate compartments. The side walls 7 of said holder are cut away at their upper ends or recessed as indicated at 8 for the more convenient extraction of the articles contained therein, and said side walls are integrally connected at their lower ends by the convex or rounded end wall 9. The edge walls 10 of said holder at their upper ends are also rounded as at 11.

The article holder 5 above described which may be constructed of leather, cardboard, sheet metal or other suitable material, is enclosed within an outer case which consists of a stamped resilient sheet metal plate bent to provide spaced side walls 12 normally extending in parallel relation to each other and integrally connected at one of their ends by the rounded or convex end wall 13. The other end of each of the side walls 12 is also rounded and bent inwardly as at 14, the edges of said curved inwardly extending walls 12 normally closely contacting with each other so that when the case is closed as shown in Figs. 1 and 3, the open end of the article holder 5 is completely closed by said ends 14 of the side walls of the case. On the opposite side edges of each of the walls 12 the integral arms 15 are formed, said arms extending at right angles to the case walls and overlapping upon each other when the case is closed as shown in Fig. 1 of the drawings.

It will thus be understood that these arms 15 prevent lateral shifting movement of the article holder 5 between the side walls of the case.

The curved or convex bottom wall 13 of the case is centrally provided with an opening 16 whereby pressure may be applied against

the end 9 of the holder 5 to project the open end of the holder beyond the end of the case so that access may be had to the contents of said holder.

5 From the above description, the construction and manner of use of this embodiment of the device will be clearly understood.

It will be noted that when the case or container is closed, the holder for the cigarettes 10 is very closely confined and held against movement within the outer sheet metal case and since the ends 14 of this case extend closely around the open end of the holder 5, the cigarettes will also be held against individual 15 shifting movement within said holder in the lengthwise direction of the latter. The single metal sheet constituting the outer case may be conveniently formed from aluminum, brass, silver, gold, or other precious metal and may 20 be suitably ornamented. The inner holder for the cigarettes can be made of leather as heretofore noted and by contrast with the outer metal case, the device when closed will present a very neat and attractive appearance. When it is desired to obtain access to the contents of the holder 5, it is only necessary to apply the finger to the lower rounded 25 end wall 9 of said holder through the opening 16 of the case and thereby force the other end 30 of the holder against the inwardly turned ends 14 of the case wall. Such pressure of the rounded ends 11 of the edge walls of the holder against the ends of the case walls, urges the latter apart to the position shown in Fig. 35 2 of the drawings, so that the open end of the article holder is projected beyond the same. It will also be noted that the arms 15 on the side walls of the case still extend upon the edge walls 10 of the holder so as to retain 40 the latter between the case walls. After the cigarette has been withdrawn, the holder may be returned to its former position, and the side walls 12 of the case will automatically return to their normal closed positions with 45 the edges of the ends 14 thereof contacting with each other over the open end of the holder 5.

In Figs. 5 and 6 of the drawings, I have shown the side walls of the outer case provided with vertically extending slots 17 to receive suitable pins 18 fixed to the opposite side walls of the holder 5. In this case the convex lower end wall of the outer case which connects the side walls 12 thereof is not provided with the opening 16 above referred to, since the article holder is shifted relative to the outer case by means of the pins 18. Otherwise, this construction is the same as that previously described.

60 In Fig. 7 of the drawings, I have shown a construction similar to that in Fig. 1, except that instead of providing the narrow arms 15 on the side walls of the case, these walls are formed on their opposite edges with the inwardly projecting flanges 19 which extend

the entire length of said walls, the opposed edges of said flanges being spaced apart sufficiently to permit of the free relative movement of said walls. Thus, in this construction, it will be understood that the opposite 70 side edges 10 of the article holder are practically completely covered and concealed from view by the flanges 19 when the case is closed.

In Fig. 8 of the drawings, I have shown the opposite side walls of the holder 10 provided with vertically spaced horizontally extending ribs 20 thereon. Thus, when the holder is projected to the position shown in Fig. 2 of the drawings, the edges of the in-turned ends 14 of the case walls 12 will engage 80 beneath the ribs 20 nearest the open end of the holder and thus support said holder upon the case walls. The other rib 20 on each side wall of the holder is provided for the purpose of limiting the outward projection of the 85 holder from the case. However, if desired, any other convenient means might be employed for this purpose in lieu of the ribs 20.

From the foregoing description, considered in connection with the accompanying drawings, the construction, manner of use and several advantages of the described embodiments of my present improvements will be readily understood. It will be seen that any one of the several constructions herein 95 disclosed provides a case or holder for cigarettes or like commodities which is simple and inexpensive in its construction as well as convenient and serviceable in practical use. The device may, of course, be produced in various 100 sizes and also in other forms than that herein specifically described. Accordingly, it is to be understood that while I have illustrated several preferred forms of the device, the same is nevertheless, susceptible of embodiment in still other alternative structures, and I accordingly, reserve the privilege of adopting all such legitimate changes in the form, construction, and relative arrangement of the 105 several parts as may be fairly embodied within the spirit and scope of the invention as claimed.

I claim:

1. A container comprising resiliently connected side walls, having relatively stiff opposed meeting end portions, an open ended article holder positioned between the side walls and adapted to be moved to project its open end outwardly beyond the meeting end portions, and means on said article holder to engage said opposed end portions of the container walls to part the end portions in advance of the projection of the contents of the article holder.

2. A container of the character described comprising an article holder, and a case therefor embodying integrally connected resiliently movable side walls having opposed meeting end portions movable towards and from each other and normally extending over 130

- and closing an open end of the article holder, said holder having cam parts adapted to be projected longitudinally between the case walls and against said meeting ends thereof 5 in advance of the holder to force said ends in relatively opposite directions and position the open end of the container beyond the ends of said case walls, the integral connection between said case walls having an opening 10 therein whereby the finger may be engaged with the end of the article holder to project the latter, each of said side walls of the case having means on its opposite edges extending over the side edges of the article holder to 15 prevent lateral shifting movement of the latter between said case walls, and said article holder being provided upon the opposite sides thereof with means adapted to coact with the edges of the separable ends of said 20 case walls to support the holder in its projected position with relation to said walls.
3. A container comprising a pair of resiliently connected side walls, meeting end portions formed integrally therewith to form a 25 complete end closure, an article holder having an open end slidable between the side walls, said article holder being adapted to be projected outwardly between the meeting edges of the end portions to position its open
- end outwardly of the end portions, and means to engage the end portions to part the meeting edges thereof prior to the projection of the contents of the article holder therebeyond. 30
4. A container of the character described comprising an article holder, and a case therefor embodying integrally connected resiliently movable side walls having opposed end portions movable towards and from each other and normally extending over and closing an open end of the article holder, said holder adapted to be projected longitudinally between the case walls and against said ends thereof to force the latter in relatively opposite directions and position the open end of the containers beyond the ends of said case 35 walls. 40
5. A container comprising resiliently connected side walls, opposed meeting end portions thereon, an article holder positioned between the side walls and adapted to be projected outwardly between the meeting end portions, and means to part the end portions in advance of the projection of the article holder. 45

In testimony that I claim the foregoing as my invention, I have signed my name hereto. 50

CHARLES L'ENFANT. 55
